[57] CLAIM

The ornamental design for a corn popper, as shown and described.

DESCRIPTION

FIG. 1 is a top, front, and left side perspective view of a corn popper, showing my new design;
FIG. 2 is a right side elevation thereof, both sides being identical;

FIG. 3 is a top plan view thereof;

FIG. 4 is a front elevation thereof; and

FIG. 5 is a rear elevation thereof.

The bottom of the corn popper is flat except for the feet and unornamented.
